UNITED STATES PATENT OFFICE.

WILLIAM SCULLY, OF DETROIT, MICHIGAN.

STOVE-PIPE DAMPER.

SPECIFICATION forming part of Letters Patent No. 236,913, dated January 25, 1881.

Application filed September 16, 1880. (No model.)

To all whom it may concern:

Be it known that I, WILLIAM SCULLY, of Detroit, in the county of Wayne and State of Michigan, have invented an Improvement in 5 Stove-Pipe Dampers, of which the following is a specification.

My invention relates to that class of stove-pipe dampers in which the damper-plate is secured to its shaft and held in any desired 10 position in the pipe without the interposition of a spring or equivalent device between the pipe and handle; and my invention consists in certain improvements in the construction and arrangement of the parts, as hereinafter 15 more fully set forth.

Figure 1 is a perspective view of my improved damper. Fig. 2 is a vertical central section through the plate and shaft.

In the accompanying drawings, which form 20 a part of this specification, A represents a section of a stove-pipe, within which a damper is secured in holes in the walls of the pipe to form bearings for the damper-shaft.

C represents the damper-plate, preferably 25 of cast metal, and in which is formed the central depression to receive the shaft, and it is also provided with the sockets a a', one at each side. The socket a is provided with a shoulder, d, adapted, when the damper is inserted 30 in the pipe, to bear against the interior of the pipe, and the socket a' has a slot or opening in its top face, with a bar, a'', extending across it. A curvilinear slot, b, is also formed in the damper-plate, which forms the tongue D in the 35 plate.

E is the damper-shaft, provided with circular bearings c, to engage with the holes in the pipe when the damper is in place. The body

of the damper-shaft E is rectangular or flattened in cross-section, to fit into the central 40 depression in the plate. A shoulder, e, is cast upon one face of the shaft, near the opposite end to the handle F. The face e' of this shoulder is inclined, while the outer face of the bar a'' is straight, and so arranged that when the 45 shaft is in place the inclined face will draw the flange h of the handle F into frictional contact with the adjacent wall of the pipe.

When the damper is placed within the stove-pipe the shaft is inserted through the hole 50 near the slotted side of the damper-plate, and is pushed along the depression in the plate until the end of the shaft enters the hole in the opposite side of the pipe. In doing this the shoulder e depresses the tongue D until 55 the inclined face of the shoulder is compelled to engage with the face of the socket, the spring of the plate always having a tendency to compel the shaft to draw the head thereof 60 against the pipe.

What I claim as my invention is—

The combination, with the damper-plate C, provided with a curvilinear slot, b, and tongue D, a socket, a, having a shoulder, d, and a socket, a', having an opening in its top, with a 65 bar, a'', extending across it, of the damper-shaft E, provided with the shoulder e, having the inclined face e', and the handle F, having the circular flange h, adapted to bear against the exterior of the pipe, substantially as described, 70 and for the purpose set forth.

WM. SCULLY.
